Filed Apr. 17, 1963, Ser. No. 74,483

Term of patent 14 years

(Cl. D58—17)

FIG. 1 is a side elevational view of an insulated portable chest showing my new design;

FIG. 2 is a top plan view thereof;

FIG. 3 is a bottom plan view thereof;

FIG. 4 is an end view thereof, as seen from the left hand end of FIG. 1;

FIG. 5 is an end view thereof, as seen from the right hand end of FIG. 1;

FIG. 6 is an enlarged, fragmentary, sectional view thereof on line 6—6 on FIGS. 1 and 2;

FIG. 7 is an enlarged, fragmentary, sectional view thereof on line 7—7 on FIG. 1;

FIG. 8 is an enlarged, fragmentary, sectional view thereof on line 8—8 on FIG. 1; and

FIG. 9 is an enlarged, fragmentary, sectional view thereof on line 9—9 on FIG. 2.

The side not shown, is substantially a mirror image of the side shown.

I claim:

The ornamental design for an insulated portable chest, substantially as shown and described.
